PRINTING PRESS TRANSFER DEVICE

Arthur Shipp, Bergenfield, N. J.

Original application August 3, 1940, Serial No. 350,251. Divided and this application April 29, 1941, Serial No. 390,880

7 Claims. (Cl. 271—61)

This invention relates to printing presses in general and more especially to transfer devices for facilitating the feeding and positioning of paper, labels, cards and the like into impression-receiving position on a press and constitutes a division of my copending application Serial No. 350,251, filed August 3, 1940.

Among the objects of the present invention, it is aimed to provide improved devices for facilitating the feeding and positioning of paper, labels, cards and the like into impression-receiving position on the printing platen of a printing press, including guides for initially stacking one or more stacks or piles of sheets of paper, labels, cards or the like face to face, with the upper face of the uppermost sheet of paper and the like exposed to facilitate simultaneously feeding into printing position one sheet of paper or the like at a time simultaneously from one or more stacks or piles.

It is still another object of the present invention to provide improved devices for facilitating the feeding and positioning of paper, labels, cards and the like into impression-receiving position on the printing platen of a printing press, including guides for initially stacking one or more stacks or piles of sheets of paper, labels, cards, or the like, either of one size or of a different size for each stack, face to face, with the upper face of the uppermost sheet of paper and the like exposed to facilitate simultaneously feeding into printing position one sheet of paper or the like at a time simultaneously from one or more stacks or piles.

It is still another object of the present invention to provide improved devices for facilitating the feeding and positioning of sheets of paper, labels, cards and the like into impression receiving position on the platen of a press, and maintaining the sheets of paper and the like in printing position during the printing operation, including guides for initially stacking one or more stacks or piles of sheets of paper and the like on a supply platform, and also grippers or pins on the platen of a press positioned relative to the guides on the supply platform to facilitate simultaneously transferring the sheets of paper from the stacks one at a time to the grippers or pins.

These and other features, capabilities and advantages of the invention will appear from the subjoined detail description of specific embodiments thereof, illustrated in the accompanying drawings in which

Figure 1 is a fragmental transverse section of

a printing press and feeder equipped with the improvements constituting the present invention;

Fig. 1a is a plan of a printing platen equipped with grippers of the type illustrated in Figs. 2 and 3;

Fig. 2 is a top plan view of one form of gripper;

Fig. 3 is a longitudinal section on the line 3—3 of Fig. 2;

Fig. 4 is a bottom plan view of the device shown in Fig. 2;

Fig. 5 is a transverse section on the line 5—5 of Fig. 3;

Fig. 6 is a longitudinal section of another form of gripper or pin;

Fig. 7 is a fragmental section on the line 7—7 of Fig. 1 showing one form of guides to facilitate stacking one or more stacks or piles of sheets of paper or the like;

Fig. 7a is a section on the line 7a—7a of Fig. 7;

Fig. 8 is a fragmental perspective of a pair of guides of the embodiment illustrated in Fig. 7;

Fig. 9 is a fragmental plan showing a modification of the guides shown in Fig. 8;

Fig. 10 is a fragmental rear elevation of the supply platform of a feeder equipped with another arrangement of guides;

Fig. 11 is a fragmental plan view of the embodiment illustrated in Fig. 10;

Fig. 12 is a plan view of another form of pin or gripper; and

Fig. 13 is a longitudinal section on the line 13—13 of Fig. 12.

In the embodiment illustrated in Fig. 1, there is shown the printing press platen 1 typical of that extensively used today, such as the Chandler & Price press, equipped with a feeder 2 of the type extensively used today such as the Miller automatic feeder disclosed in Patent No. 1,194,327. With this combination of platen 1 and feeder 2, there is provided a supply platform 3 for receiving a stack 4 of material to be printed. The sheets from the stack 27 are fed to the platen 1 by a combination of devices, including a suction cup such as the suction cup 5 which picks up the uppermost sheet of the stack 27, raising it, whereupon the feed grippers 6 on the carrier 7 are moved rearward to receive and grip the sheet so raised, which carrier 7 is then carried forward into engagement with pins or grippers on the platen 1 while the platen 1 is in open, slightly inclined position. According to the present invention, the platform 3 has secured

thereto a plate 8 equipped with guides for positioning the stacks on the plate 8 relative to the front stops 9 of the feeder 2. This plate 8 may be secured to the platform 3 by any suitable means, such for instance as the set screw 10 extending through an opening in the plate 8, and screw threadedly connected to a shoe slidably mounted in a slot in the platform 3. On the plate 8 adjacent the ends thereof there are provided the bearing brackets 14 for the polygonal shaped rod 16, in the present instance, rectangular in cross section. On this rod 16, there are slidably mounted the guiding brackets 17 arranged in pairs. The brackets 17 each consist essentially of the block 19 having a rectangular opening to receive the rod 16, to fix the bracket 17 against rotation on the rod 16 while permitting slidable movement thereon.

In order to anchor the block 19 against slidable movement on the rod 16, there is provided the set screw 20 passing through the block 19 to engage the rod 16 and frictionally anchor the block 19 in position on the rod 16 in the usual way. To the front face of the block 19 there is provided the angle iron strip 21 having a web 22 in alignment with the front face of the block 19, and a web 23 extending at right angles thereto and forwardly thereof. The bracket 18 is substantially identical to the bracket 17 except that the web 24 of the angle iron strip 25 extends from the edge of the web 26 removed from the bracket 17 while the web 23 extends from the edge of the web 22 removed from the bracket 18. With this arrangement of the webs 23 and 24, see Fig. 7, the uppermost brackets 17 and 18 of a pair may cooperate with a stack 27 of paper sheets or labels, cards or the like, illustrated in dash-and-dot lines.

With the embodiment illustrated in Fig. 7, the successive pairs of brackets 17 and 18, all mounted on the same rod 16, may position a plurality of groups of labels, cards, sheets of material and the like of different widths, but of one and the same length. In other words, the cards of the stack 27 would have the same dimension from the stops 9 to the inner faces of the webs 22 and 26 of the brackets 17 and 18 relative to the other pairs, but the widths thereof, that is, between the inner faces of the webs 23 and 24 of the successive pairs, may vary. Or, to state it differently, the brackets 17 and 18 of each pair may be adjusted relative to one another to accommodate different widths.

If the card or label such as the label 28 of Fig. 9 has one straight edge such as the edge 29 and an opposite curved edge, such as the edge 30, the web 31 of the bracket 32 will be considerably wider than the web 33 of the bracket 34. In all other material respects, the brackets 34 and 32 of a pair are identical to the brackets 17 and 18 of the pair illustrated in Fig. 8.

When the material to be printed is arranged in stacks 27, the feeder 2 will be provided with suction cups 5 positioned one above each stack 27. Thereupon, when the operation of the machine is started, the cups 5 will initially and simultaneously engage the upper faces of the sheets of paper or the like in the stacks 27, and feed them upward for engagement by the feed grippers 6 on the carrier 7 which will thereupon feed the sheets of paper or the like so being advanced by the carrier 7 into engagement with grippers on the platen 1. To cooperate with the guides formed by the brackets 17 of the embodiment illustrated in Fig. 1, and assuming that the sheets

of paper or the like are not only of the same length but also of the same width as shown in Fig. 1a, then there will be secured to the platen 1 a corresponding number of pairs of grippers 35, the two grippers of each pair being positioned on the platen 1 to align with the position of the brackets 17 of its associated pair to enable the feed grippers 6 to feed the material from a pair of guides 17 to its associated pair of grippers 35.

In the embodiments shown in Figs. 1, 2 and 3, the form of gripper, designated 35, consists essentially of three spring metal strips 36, 37 and 38 secured to one another by the fastening bracket 39. The housing 39 consists essentially of an upper plate portion 40 provided with a rear downwardly extending portion 41 having an opening therein to enable the metal strips 37 and 38 to extend therethrough and then provide with a rearwardly extending portion 42 having an intermediate sharp pointed prong element 43, the forward edge of which is only slightly bent upwardly as shown in Fig. 3, with two prong elements 44 and 45, one to either side of the prong 43 extending forwardly and terminating in the portions 46 and 47 respectively, short of the front end of the prong 43 and having upward bends considerably more acute than the upward bend of the prong 43. At the front end of the portion 40 of the housing 39, there is provided a downwardly extending portion 48 with a tongue 49 cut out of the portion 40 and slightly waved, with the upper convex face of the tongue 49 engaging the lower face of the strip 38 and pressing it snugly against the strip 37 in turn to press the forward portion of the strip 37 against the lower face of the portion 40. The rear lower face of the strip 36 above the housing 39 is secured to the upper face of the portion 40 in any suitable way such as welding, soldering, or the like. The forward portions of the strips 37 and 38 also are preferably secured to one another, by welding, soldering or the like, and similarly the upper forward face of the strip 37 is preferably secured to the lower face of the portion 40 of the housing 39 by welding, soldering or the like.

The portion 41 furthermore has two prongs 141 extending down below the lower level of the prong elements 43, 46 and 47.

In the present instance, the sides of the upper strip 37 rearward of the portion 40, have ears 50 bent from the edges thereof to form journals for the pin 51 of the knurled wheel 52 extending through the opening 53 in the upper strip 36 and also extending through an opening 54 in the intermediate strip 37 registering with the opening 53 to enable the roller 50 to engage the upper face of the strip 38.

The prongs 43, 46 and 47 are provided to secure the gripper or pin 35 to the sheets of paper 55 secured to the upper face of the platen 1 in the well-known method customary in the trade, the prong 43, as shown in Fig. 3, piercing the paper 55 and being buried under the same with the prongs 46 and 47 to either side thereof disposed to engage the upper exposed face of the paper 5 while the prongs 141 pierce the paper 55, as shown.

The rear ends of the strips 36, 37 and 38 have a predetermined curve or bend, as shown, the rear end of the strip 38 being slightly bowed so that its extreme rear edge snugly engages the upper face of the paper 55 to prevent a sheet of paper, label, card or the like being obstructed by it when fed into gripping engagement by the

gripper 6. The rear end of the strip 37 on the other hand is bowed to extend upward at a considerable angle, in the present instance, of about forty-five degrees to the upper face of the paper 55, and adjacent the upwardly bowed end of the outer strip 36. The two outer strips 36 and 38 are preferably composed of half tempered steel of about .009 of an inch in thickness, while the intermediate strip 37 is of an extremely flexible steel such as high grade Swedish steel of about .004 of an inch. With this type of gripper, the intermediate strip is particularly yieldable to prevent interfering with the ready reception of a very thin sheet of paper in the act of advancing the same while the outer strips 36 and 38 serve an entirely different purpose. While the strip 38 might be as flexible as the intermediate strip 37, a strip composed of half tempered steel, if thin enough, will serve the purpose, so long as it snugly engages the upper face of the paper 55 to prevent the sheet of material being fed from unintentionally passing under the strip 38 between the strip 38 and the paper 55. The strip 36, on the other hand, should be of a stiffer nature than that of the strip 37 to act as a buffer, reinforcement and protection to the intermediate strip 37. The free end of the strip 37 need not necessarily engage the free end of the strip 36 so long as the portion 56 thereof is spaced from the strip 36 and in engagement with the upper face of the strip 38 so that the bowed portion 56 of the intermediate strip 37 may cooperate with the upper face of the adjacent portion of the strip 38 frictionally to anchor the card, sheet of paper, or the like in printing position. The portion 41 in these pins is provided to serve as the forward stop for the card, sheet of paper, or the like, that is, the material to be printed, the strips 37 and 38 thus cooperating with the portion 41 to anchor the strip in printing position.

Still furthermore, the knurled wheels 52 will ride on the edges of the material to be printed and provide additional frictional contact due to the resiliency of the strip 36 so that the material to be printed may be frictionally anchored in position against the strip 38 between the bowed portions 56 and knurled wheels 52. With the pivot point, to-wit: the pin 51 of the knurled roller 52 disposed above the strip 37, the arc of the roller 52 exposed below the strip 37 for engagement with the material to be printed, will cooperate to facilitate ready feed of the sheet of material to be printed while being advanced into and out of printing position.

In operation with the platen 1 in descended open position, and the material to be printed in a stack 27, the nozzle 5 will be lowered into engagement with the upper face of the top sheet in the stack 27 whereupon the suction nozzle will act to pick up the uppermost sheet and then rise with the sheet so picked. Thereupon the feed grippers 6 of the carrier 7 will move to receive the sheet so raised, grip it, and will then advance it into gripping engagement with the grippers 35 on the platen 1. Thereupon, the carrier 7 will clear the platen 1 and the platen 1 will close into printing position. After the impression, the platen 1 will open, and upon assuming the position shown in dash-and-dot lines in Fig. 1, the removing fingers 57 on the shaft 58 at the end of the arm 59 will swing over, open its jaws, and engage the sheet held by the grippers 35 and remove the same, whereupon the platen 1 will return to the original open position ready to receive the next feed.

The form of gripper 60, shown in Fig. 6, differs

from the form of gripper 35 shown in Figs. 2, 3, 4 and 5 primarily in that it dispenses with the wheel 52 and consequently, of course, with the function performed by the wheel 52, in this case depending entirely upon a frictional lock, namely, that between the bowed portion 61 of the intermediate strip 62, and the lower strip 63.

The gripper or fork shown in Figs. 12 and 13 is of the type which dispenses with the securing prongs, such as the prongs 43, 46 and 47 of the form shown in Fig. 2. The lower strip 64 corresponding to the strip 38 of the embodiment shown in Fig. 2 is enlarged at its front end into the bifurcated extension 65. The intermediate strip 66 composed of high grade Swedish steel of about .004 of an inch in thickness, is secured at its free end to the rear end of the upper face of the extension 65 by soldering, welding and the like, and then bent over to form the flange 68 folded upon the front end of the upper strip 67 and secured thereto by soldering, welding or the like. The upper strip 67, similar to the strip 36 of the embodiment illustrated in Fig. 2, is provided with a knurled wheel 69 which also extends through an opening in the intermediate strip 66 and normally rests on the upper face of the lower strip 64 so that the sheet of paper constituting the material to be printed is frictionally secured against the lower strip 64 by the knurled wheel 69 and the bowed portion 70 of the intermediate strip 66 highly flexible, high grade Swedish steel grip 66.

The fork shown in Figs. 12 and 13 is secured to a support by a screw or the like, not shown, passing through the recess 71 into the support. The support may be the platen, such as the platen 1 in Fig. 1, when the sheet to be printed remains in the fork and thereby positioned on the platen during the printing operation, or the fork may be secured to a portion of the frame adjacent the edge of the platen to facilitate removing the fork after the sheet to be printed has been positioned and before the platen is moved into closed printing position.

The embodiment shown in Figs. 10 and 11 of guides for the stacks of sheets on the platform 3, before being advanced onto the platen 1, presents as an advantage added flexibility. With this embodiment, labels, cards, sheets of paper or like work of different sizes, both as to width as well as length, may be stacked in position to be advanced onto the platen 1. As an instance, here, instead of the plate 8 shown in Fig. 7, there is provided a plate 12 of sufficient thickness so that it may accommodate the slots 73, 74 and 75 with the diminished necks 76. The slots 73, 74 and 75 are provided to accommodate the bases 77 of the pins 78 which extend up through the posts 79 which, in turn, are provided with polygonally shaped diminished ends 80 slidably mounted but fixed against rotation in the necks 76 of the slots 73, 74, 75 for supporting arms 81 and 82 angular or polygonal in cross section to either side thereof slidably to receive the blocks 83 of the angle iron strips 84 and 85. The blocks 83 are slidably mounted on the arms 81 and 82 but fixed against rotation preferably through an angular formation of the slots in the blocks 83 through which the angular arms 81 and 82 extend. The strips 84 and 85 are arranged in pairs, the web 86 of the strip 84 extending from the edge of the strip 84 remote from the strip 85, and the web 87 extending from the edge of the strip 85 remote from the strip 84. It will be noted that the spacing of the strips 84 and 85 of each pair are independent of one another so that the material stacked by

each pair of strips 84 and 85 may be different in width than that of either or both of the other pairs of strips 84 and 85.

The pins 78 extend up beyond the upper ends of the brackets formed by the posts 79 and arms 81 and 82 and are preferably threaded at the upper ends to receive the wing nuts 88 by means of which the brackets may be anchored in the plate 72 at a predetermined distance removed from the edge 89 or from the stop wall 9, shown in Fig. 7, when the plate 72 is secured on the platform 3. In this way, it will appear that the individual pairs of strips 84 and 85 may be anchored at different distances from the edge 89 or stop 9 to accommodate stacks of different 15 lengths relative to one another.

The arrangement of the embodiment shown in Figs. 10 and 11 also provide for greater widths than that made possible by the combined lengths of the arms 81 and 82 by using the strip 84 of 20 the first or second pair for alining one side of the sheet of material to be printed and the strip 85 of the second or third pair, in which case the intermediate strips 85 and 84 will, of course, be removed. The strips 84 and 85, while normally 25 slidable on the arms 81 and 82, respectively, may be anchored in place by the set screws 90 extending through the blocks 83 and frictionally engaging the arms 81 or 82 in anchoring or locking position.

The plate 72 may be secured to the platform 3 by a set screw 91 similar to that shown in Fig. 7a screw threadedly connected to the shoe 191 slidably mounted in the slot 92 formed in the platform 3, the set screw 91 extending 35 through an opening in the plate 72 similar to the manner of securing the plate 8 to the platform 3.

The guides 17 and 18 of the embodiment shown in Figs. 7 and 8 are slidably mounted on 40 the bar 16 to adjust for the width of the material to be printed. The space between the stop 9 and the rear faces of the webs 22 and 24 is adjustable by moving the plate 8 relative to the platform 3. When the spaces of the guides 17 and 18 relative to one another have been determined, the set screws 20 will be actuated to 45 anchor the guides 17 and 18 relative to one another on the bar 16, and when the space between the stop 9 and the rear faces of the webs 22 and 50 24 has been determined for a given job, the set screws 10 will be actuated to anchor the plate 8 in such position on the platform 3.

In operation, after the printing impression has taken place, and the platen 1 has moved into 55 the position shown in dash-and-dot lines in Fig. 1, as is well known in the Miller feeder, such as disclosed in Patent No. 1,194,327, issued to E. Cheshire, dated August 8, 1916, the fingers 57 will be actuated to grip the sheet 93 and carry it 60 over to the trough 94 and deposit it therein.

It is obvious that various changes and modifications may be made to the details of construction without departing from the general spirit of the invention as set forth in the appended 65 claims.

I claim:

1. The combination of a feeder platform having stack forming guides operatively associated therewith corresponding in position to the grippers on the platen of a printing press, said guides including a transversely extending support, and wings slidably mounted on said support to correspond to the width of the material to be printed.

2. The combination of a feeder platform having stack forming guides operatively associated therewith corresponding in position to the grippers on the platen of a printing press, said guides including a transversely extending support longitudinally adjustable along said platform, and wings slidably mounted on said support corresponding to the width of the material to be printed.

3. The combination of a feeder platform having a stop wall at the rear thereof, a plate secured to said platform, transversely extending supporting means secured to said plate, pairs of guides mounted on said supporting means transversely slidable but fixed against rotation, and means for anchoring said guides at predetermined spaces from one another on said supporting means.

4. The combination of a feeder platform having a stop wall at the rear thereof, a plate secured to said platform, a transversely extending bar secured to the plate, pairs of guides slidably mounted on said bar but fixed against rotation, the guides of each pair having rearwardly extending flanges spaced from one another according to the width of the material to be printed, said plate being adjustably secured to said platform to adjust the position of the guides relative to said stop wall to correspond to the length of the material to be printed.

5. The combination of a feeder platform having a stop wall at the rear thereof, a plate secured to said platform, a transversely extending bar secured to the plate, pairs of guides slidably mounted on said bar but fixed against rotation, the guides of each pair having rearwardly extending flanges spaced from one another according to the width of the material to be printed, said plate being adjustably secured to said platform to adjust the position of the guides relative to said stop wall to correspond to the length of the material to be printed, the rearwardly extending flange on one of said guides being longer than that of the flange on its associated guide to accommodate a sheet, card or label having a rounded edge on one side.

6. The combination of a feeder platform having a stop wall at the rear thereof, a plate secured to said platform, a plurality of brackets having transversely extending arms mounted on said plate independent of one another, guides mounted on said arms and having rearwardly extending webs, said guides being slidably mounted on said arms to space the webs of a pair according to the width of the material to be printed, means for securing the guides against movement when so positioned, said brackets being slidably mounted on said plate to adjust for the length of the material to be printed, and means for securing the brackets against movement when properly positioned.

7. The combination of a feeder platform having a stop wall at the rear thereof, a plate secured to said platform, a plurality of brackets having transversely extending arms mounted on said plate independent of one another, guides mounted on said arms and having rearwardly extending webs, said guides being slidably mounted on said arms and removable therefrom to space the guides selected according to the width of the material to be printed, and means for securing the guides against movement when selected and positioned.

ARTHUR SHIPP.
